UNITED STATES PATENT OFFICE.

ERWIN ROSENHEIM, OF PHILADELPHIA, PENNSYLVANIA.

VENTILATOR.

1,011,494.

Specification of Letters Patent. Patented Dec. 13, 1911.

Application filed July 16, 1910. Serial No. 572,270.

To all whom it may concern:

Be it known that I, ERWIN ROSENHEIM, a citizen of the United States, and a resident of the city of Philadelphia, in the county of Philadelphia and State of Pennsylvania, have invented certain new and useful Improvements in Ventilators, of which the following is a specification, reference being had to the accompanying drawings.

This invention particularly relates to that class of ventilators which are applicable to railway cars or similar vehicles. The form of this invention hereinafter described provides a car with a plurality of ventilators, each comprising a casing preferably in the form of a cylindrical quadrant opening into the car, and having ports in each of its longitudinal plane walls, and provided with a rhombohedral extension forming an obliquely depending duct extending through the floor of said car from one longitudinal wall of said casing, and opening exterior to said car; a sliding gate having angularly disposed wings mounted for reciprocation in said casing and provided with apertures which are registerable with the respective ports in the walls of said casing, said gate being provided to close said ports or to vary their respective areas when desired; and a plurality of similar ventilators disposed at the top of said car.

This invention further includes all of the novel features of construction and arrangement hereinafter more definitely specified.

In the accompanying drawings, Figure 1 is a partial side elevation and fragmentary sectional view of a railway car, embodying a convenient application of this invention; Fig. 2 is a perspective view of a ventilator unit showing the form of this invention which is adapted to direct air through the car floor; Fig. 3 is a fragmentary end elevation of the ventilator unit which is adapted to direct air through the top of the car; Fig. 4 is a transverse vertical sectional view of the ventilator unit shown in Fig. 2, taken on the line 4-4 of Fig. 5; and Fig. 5 is a vertical longitudinal sectional view of the ventilator unit shown in Fig. 2, taken on the line 5-5 of Fig. 4.

In said figures, the car 10 comprises the floor 11, the main roof 12 and the super-roof 13. Said car is provided with the seats 14, one being located at each window 15 and below each transom opening 17, which

are normally provided with transom windows 18, between said main-roof and super-roof. Beneath each seat 14, is disposed a ventilator unit 20, which, as best shown in Figs. 2 to 5 inclusive, includes a quadro-cylindric casing 21, comprising the curved wall 22 and the adjacent plane angularly disposed walls 23 and 24, respectively, having elongated ports 25 and 26 for the passage of air therethrough. The wall 23 is in unitary relation with the curved wall 22, and the wall 24, is formed of a separate plate, preferably of sheet metal. Said casing 21 is provided with an air duct 28 of rhomboidal form, having a flange 29 which is joined with the casing 21 by the turned over flange 30 of said casing. Said flange 30 also embraces the projecting edges of the wall 24, which forms a diaphragm between said casing 21 and duct 28. The ventilator 20 is regulated and controlled by the slide-gate 31 comprising the angularly disposed wings 32 and 33, and is mounted for reciprocation within said casing, and maintained in position by the angle flanges 34 and 35 slidably engaging the free edges of the respective wings 32 and 33. Said wings 32 and 33 are respectively provided with apertures 37 and 38, which are arranged to register with the ports 25 and 26 respectively, when the ventilator is opened to its maximum extent, and to be shifted out of registry to close said ports.

The wing 32 is provided with the knob 40 whose shank 41 extends through the slot 42 in the wall 23 of the casing, said slot 42 being of such length as to limit the movement of the slide-gate 31, so that when said gate is shifted to the limit of its movement in the direction of the arrow indicated in Fig. 3, the shank 41 will engage the right hand end of the slot 42 as shown in Fig. 2 to register the apertures 37 and 38 with the respective ports 25 and 26, and when shifted in a direction opposed to that indicated by the arrow in said figure, said shank 41 will engage the left hand end of said slot, and limit the movement of the gate 31 in such position that the ports 25 and 26 will be closed by the web of the respective wings 32 and 33.

The ventilator units 45 shown in Fig. 3 are each provided with a flange 46, and are adapted to be inserted in the transom openings 17, between the main-roof 12 and the super-roof 13, as best shown in Fig. 1, with

their flanges 46 secured to the jambs 47 of the transom openings 17. In other respects, said ventilator unit 45 is similar to the ventilator unit 20.

- 5 As may be best seen with reference to Fig. 1 a ventilator 20 is disposed beneath each of the seats 14 and has its flanges 30 secured to the car floor 11, the air ducts 28 of said ventilators being obliquely disposed in different 10 directions through said floor 11, beneath the alternate seats upon each side of the car, and the ventilators which are disposed under opposite seats having their air ducts 28 disposed in opposite directions.
- 15 In the normal operation of the ventilating system herein described, the ventilators 20 having their air ducts 28 depending toward the direction of movement of the car, may have their slide gates 31 closed, and the ventilators having their air ducts 28 extending rearwardly with respect to the direction of movement of the car, having their slide gates 20 31 opened, so that, as may be readily seen, an outward draft is created in the ducts 28.
- 25 This draft is effected by the rapid movement of the outlets of the rearwardly inclined ducts, projecting beyond the car flooring, through the air exterior thereto, to effect the drawing of the foul air from the interior 30 of the car through the ventilators beneath alternate seats, and beneath the seats in staggered relation at the opposite sides of said car.

It may be here noted that by drawing the 35 foul air from the bottom of the car effects a corresponding inrush of fresh air through the ventilators at the top and the crevices in the sides of the car, and the fresh air thus admitted is uniformly circulated and 40 finally drawn out through the ventilators at the bottom of the car, together with the heavier gases which normally settle at the floor, so that it is obvious that the more 45 poisonous gases are permitted to escape directly through the car floor where they normally collect, and their circulation in the upper strata is thus avoided.

While the theory of the air circulation within a car equipped with this type of 50 ventilator is not positively known, it is believed that air is admitted at the top and emitted at the bottom because of two principal factors. These factors, briefly stated, are, the 55 projection of the air ducts below the lowermost portion of the car floor, which causes a downward deflection of the air currents

impeding thereagainst, and a consequent drawing of the car air therethrough; and, secondly, the greater extent of the sides of the floor ducts opposed to the external air 60 currents when compared with the relatively narrow end walls of the ducts of the ventilators adjacent to the ceiling.

It is not desired to limit this invention to the precise details of construction and 65 arrangement herein set forth, as it is obvious that various modifications may be made therein without departing from the essential features of the invention as defined in the appended claims. 70

Having thus described my invention, I claim:

1. A ventilator comprising a casing substantially triangular in cross section having 75 its adjacent walls provided respectively with inlet and outlet ports, and a slide-gate having angularly disposed wings operative to close said ports simultaneously, and provided with apertures registerable therewith the side opposite said adjacent walls, serving 80 to direct a draft from said inlet ports to said outlet ports.

2. A ventilator comprising a sectoral casing having its adjacent walls provided with 85 ports, a slide-gate having angularly disposed wings operative to close said ports simultaneously and provided with apertures registerable therewith, and an obliquely extending duct depending from said casing.

3. A ventilator comprising a quadro-cylindrical casing having ports in its longitudinal plane walls, a duct depending from said 90 casing operative to direct air therefrom, a slide-gate having wings operative to close said ports and provided with apertures registerable therewith. 95

4. A ventilator comprising a quadro-cylindrical casing, having ports in its longitudinal plane walls, a duct depending obliquely 100 from said casing operative to direct a current of air, a slide-gate having wings operative to close said ports and provided with apertures registerable therewith said duct terminating in a plane parallel to the line of motion. 105

In witness whereof, I have hereunto set my hand this first day of July, A. D. 1910.

ERVIN ROSENHEIM.

CLIFTON C. HALLOWELL,
ALEXANDER PARK.

Correction in Letters Patent No. 1,011,494.

It is hereby certified that in Letters Patent No. 1,011,494, granted December 12, 1911, upon the application of Ervin Rosenheim, of Philadelphia, Pennsylvania, for an improvement in "Ventilators," an error appears in the printed specification requiring correction as follows: Page 2, line 86, for the word "operative" read *coöperative*; and that the said Letters Patent should be read with this correction therein that the same may conform to the record of the case in the Patent Office.

Signed and sealed this 30th day of January, A. D., 1912.

[SEAL.]

C. C. BILLINGS,
Acting Commissioner of Patents.
